United States Patent Office.

WILLIAM J. ARRINGTON, OF JEFFERSON COUNTY, GEORGIA.

Letters Patent No. 92,143, dated July 6, 1869.

IMPROVEMENT IN PLOWS.

The Schedule referred to in these Letters Patent and making part of the same.

To all whom it may concern:

Be it known that I, WILLIAM J. ARRINGTON, of Jefferson county, Georgia, have invented a new and useful Improvement in Plows, of which the following is a full, clear, and exact description, reference being had to the accompanying drawings, forming a part of this specification, in which—

Figure 1 represents a side elevation thereof.

Figure 2, sweep-side guide, the same being a modification of landside.

Like letters of reference indicate corresponding parts.

One of the improvements consists in making the landside or bar of the plow with a bevel or flange, and of such shape and dimensions as admits through it, of the application of any turning plowshare, and especially when the universal plow-stock, below described, is used.

Viewed from its straight or landside aspect, the landside presents the general appearance of a triangle, with its hypothenuse or long edge next the ground, when in position for use, which edge may be either straight in its entire length, as in case where the plow-share is to be heavily pointed, as represented in red line, fig. 1, or only so for six or seven inches of its hindmost part, and then curved upward towards the share-edge, when the point of the plow-share to be used is intended to be only of the thickness of its other parts.

This ground edge is, in all instances, slightly bevelled or expanded to the right or mould-board side, to give a greater guiding and more durable surface.

The hindmost edge inclines suddenly downward for a short distance, and then runs (making width of heel-part) nearly parallel with ground line.

The anterior line or edge, where plowshare applies, is curved, from above downward, at any desired angle, and has, on its right or mould-board side, a semi-oval bevel or flange, A, which flange takes the same angle downward and to the right with the landside proper.

Viewed from its anterior aspect, this bevel or flange commences at the highest or truncated top of the bar or landside, is from four (4) to five and a half (5½) inches in length, two or two and a half inches in width, and comes nearly to a feather-edge on its right border. It is slightly curved on its under or standard side, is perforated by one or more holes, h, from before backward, through which pass the bolt or bolts b, securing at once the plowshare, landside, (by means of its flange,) and standard, firmly together.

The landside is also perforated, near its upper part, by a countersunk hole, B, through which passes the bolt, at once binding together the landside, standard, and brace.

The advantages claimed for this flanged landside, are—

First, its cheapness.

Second, its adaptability to all turning mould-boards, to which it gives the desired turning-angle.

Third, its easy application to a universal stock, and to which (when the landside is removed) any other than turning plowshares may be applied.

The plow-stock, to which this landside is adapted and peculiarly applicable, is composed of wooden beam, handles, and round, of ordinary structure, in the main, a slotted and curved wrought-iron standard, S, and a straight iron rear-brace, O.

The standard is made of proper-sized bar-iron, bent on itself, with a slot from its beam to share-end, and grasps, by its upper end, the beam at nearly right angles; is perforated laterally by (3) three holes, the upper one securing, by bolt, the beam and standard together, the next lower one securing the bolt that binds together the landside, standard, and brace.

The lower one is used only when the sweep-side guide, fig. 2, D, (a modification of the series of landsides,) is applied, whilst the sweep, or similar plow, is being used.

The brace C is fastened, (being a straight bar,) at its lower end, in the slot of the standard S, by the same bolt B that passes transversely through landside, standard, and brace, ranges upward and backward between the handles to a mortise in rear end of the beam, where it, the handles, and beam, are held firmly together by bolt i. It is perforated, just after leaving the standard, by a hole, through which passes a bolt, k, securing it and lower end of handles together.

It will be seen, that a discovery has been made in this stock, by such combination and method of attachment of its parts, as to give greater strength and durability than heretofore known in any stock of same material, and that the brace in angle of direction and mode of attachment to both standard and beam, is novel, and that the peculiar curvature of the standard is such as at once to make it universal and applicable to the flanged landside.

Having thus fully described my invention, what I claim as new, and desire to secure by Letters Patent of the United States, is—

1. The flange A of the landside, substantially as shown herein specified.

2. The combination of flange A, standard S, and brace C, (with its attachment to handles,) the whole constructed substantially as and for the purposes hereinbefore described.

Witnesses: WM. J. ARRINGTON.

C. BESTOR,

EDM. F. BROWN.
